2,382,079

NEEDLE THREADER

John C. Lounsbury, Washington, D. C.

Application June 8, 1944, Serial No. 539,252

7 Claims. (Cl. 223—99)

This invention relates to needle threaders and has for its primary object to provide an efficient device for accurately and quickly threading hand sewing needles.

More particularly, the present invention relates to modification of and improvements upon the type of needle threader shown in my U. S. Letters Patent No. 2,210,943, dated August 13, 1940, whereby the threader is especially adapted for the threading of hand sewing needles.

An important object of the present invention is to provide a needle threader of the above kind in which cooperating fingers are automatically actuated for rotating the needle so as to properly position the eye of said needle for reception of the threading pin and preparatory to the movement of said threading pin through the eye of the needle in the threading operation.

A further object of the present invention is to provide a needle threader of the above character in which a sliding actuating plate operates to place a spring under compression so that the latter will swing a lever for moving the threading pin through the eye of the needle, and in which movement of the actuating plate in a direction to relieve the compression of the spring effects withdrawal of the threading pin from the eye of the needle and clamping of the loop of the thread which has been passed through the needle eye, thereby causing the thread to be pulled further through the eye of the needle for completing the threading operation immediately following withdrawal of the threading pin from the needle eye.

Still another object of the present invention is to provide a needle threader of the above character in which the needle rotating fingers are spring-actuated for rotating the needle, and in which the sliding actuating plate causes separation of the needle rotating fingers immediately subsequent to withdrawal of the threading pin from the needle eye.

Other objects and features of the invention will become apparent from the following description when considered in connection with the accompanying drawings, and the invention consists in the novel form, combination and arrangement of parts hereinafter more fully described, shown in the drawings and claimed.

In the drawings, wherein like reference characters indicate corresponding parts throughout the several views—

Figure 1 is an enlarged perspective view of a needle threader constructed in accordance with the present invention.

Figure 2 is a horizontal section taken substantially on the plane of the line 2—2 of Figure 1 and enlarged further, the parts being positioned ready for the needle threading operation.

5 Figure 3 is a vertical longitudinal section taken substantially on the line 3—3 of Figure 2.

Figure 4 is a transverse vertical section taken on the line 4—4 of Figure 3.

10 Figure 5 is a view mainly in horizontal section on line 5—5 of Figure 3, but also showing an end of the installed crank lever and the adjacent threading pin.

15 Figure 6 is a fragmentary detail view showing the needle rotating fingers in position preparatory to being actuated for rotating the needle.

Figure 7 is a fragmentary section somewhat similar to Figure 2, but showing the threading pin projected through the eye of the needle and the needle rotating fingers positioned to grip the 20 needle eye after having rotated the needle.

Figure 8 is a perspective view illustrating the manner in which the threading pin forces the thread loop through the eye of the needle.

Referring in detail to the drawings, the invention includes a flat substantially rectangular casing 5 that is open at the ends. Fitted within and secured upon the bottom of the casing 5 is a plate 6 having transverse upstanding ribs 7 and 8 at the ends thereof whose upper faces contact 25 the undersurfaces of the top wall of casing 5 at the ends of the latter. The top and bottom walls of casing 5 and the end of plate 6 provided with ribs 7 are cut away intermediate the sides thereof so as to provide an entrance slot 9 for the thread. The inner shoulder of rib 7 at one side of slot 9 serves to provide a fixed thread loop clamping jaw at 10, as and for a purpose which will be later made apparent. At the inner end of slot 9, the plate 6 and the casing 30 are provided with vertically aligned notches at one side of said slot 9 as indicated at 11. The notches 11 in the casing are slightly deeper than that in the plate 6 as brought out in Figure 4, and centrally of the notch 11 in plate 6 there is 35 provided a vertical narrow slot 12 as shown more clearly in Figures 4 and 6 that ultimately receives the thread as it is looped about the adjacent end of the casing and across the notches 11 at the adjacent side of the slot 9. At the 40 opposite side of the inner end portion of slot 9, and directly in transverse alignment with the notches 11, the bottom wall of the casing 5 has a projecting portion 13 in the upper surface of which is provided a recess 14 adapted to form a 45 seat for reception of the eye end of the needle 50

55

to be threaded. At the side of slot 9 where the notches 11 are formed, the plate 6 is provided with a partition block 15 that is spaced slightly rearwardly from the adjacent portion of the rib 7 so as to provide a transverse space at 16 in which is snugly received and slidably guided an end portion of a threading pin 17. In this way, the threading pin has its end portion maintained in alignment with the slot 12 and the needle seat 14 transversely of the device, so that when the threading pin is moved transversely of the casing in a direction toward the needle eye its free end will engage the thread and force the same in the form of a loop 18 through the eye 19 of the needle 20 as clearly illustrated in Figure 8.

Pivoted upon the plate 6 within the casing 5 is an L-shaped bellcrank lever 18 whose pivot 19 is located near a rear corner of the casing. Lever 18 has a short arm extending transversely of the casing toward the opposite side of the latter as at 18a and a longer arm 18b that extends forwardly along one side of the casing to a point adjacent the front end of the latter. The front end of the arm 18b is bifurcated to straddle the partition block 15 and cooperate with the latter for limiting the swinging movement of said lever 18. One furcation 20 of the arm 18b is slotted at 21 to loosely receive an angularly bent end 22 of the threading pin 17 whereby the latter is operatively connected to said lever 18. Slidably mounted on the plate 6 adjacent the front of the casing and at the side of the latter opposite to that at which the lever arm 18b is located is an actuating plate 23. Plate 23 is guided by pins 24 and 25 engaged in longitudinal elongated slots 26 and 27 of said plate 23. A longitudinal elongated slot 28 is provided in the top wall of casing 5, and fixed to and projecting upwardly from the plate 23 is a pin 29 that also loosely extends upwardly through the slot 28 and terminates at its upper end in a knob 30. By pressing rearwardly on pin 29, the plate 23 may obviously be slid rearwardly. A U-shaped leaf spring 30 is disposed in the casing above the plate 6 and has one end secured at 31 to the free end of lever arm 18a, the other end of said spring 30 being secured at 32 to the rear end of plate 23 adjacent the outer side of the latter. The arrangement is such that when plate 23 is slid rearwardly, spring 30 is placed under compression so as to rock lever 18 in a direction to cause threading pin 17 to move transversely of the casing for forcing the thread loop 18 through the needle eye 19. On the other hand, when the plate 23 slides forwardly, compression of spring 30 is relieved and lever 18 is caused to swing to the full line position of Figure 2 wherein the threading pin 17 is withdrawn from the needle eye. In actual practice, reciprocation of threading pin 17 takes place substantially instantaneously so as to quickly thread the needle and withdraw the threading pin from the needle eye in rapid succession. However, means may be provided to releasably lock the plate 23 in its rearwardly slid position in case the pin 29 is forced rearwardly a sufficient distance to fully complete the threading movement of threading pin 17 through the needle eye. For this purpose, the forward end of slot 27 has a lateral extension 33 into which the guide pin 25 may ride as plate 23 approaches its rearward limit of movement, such action being had by reason of the tilting action of spring 30 on plate 23 at this time. In other words, spring 30, being attached to plate 23 near the outer side of the latter, acts to horizontally swing the plate

23 from the position of Figure 2 to the position of Figure 7 in case plate 23 has been shifted rearwardly to its fullest extent. This prevents retraction of the threading pin unless and until it has been given a complete threading stroke. It will be noted that the free end of lever arm 18b has a lateral inwardly extending enlargement 34, and plate 23 is provided at its inner side and adjacent its front end with a lateral enlargement 35. These enlargements are so formed that when the threading movement of pin 17 is fully completed, enlargement 34 will engage enlargement 35 and swing plate 23 in a direction to disengage pin 25 from slot extension 33, thereby permitting the return of plate 23 to its initial forward position and allowing lever 18 to retract the threading pin 17 from the eye of the needle.

As shown more clearly in Figure 5, plate 6 is provided centrally of its forward end with a relatively large slot or recess 36 within which are disposed needle rotating and needle eye gripping fingers 37 and 38. Finger 37 has longitudinal slots 39 which slidably receive pins 40 fixed to and projecting upwardly from the bottom of casing 5. In this way, finger 37 is mounted for longitudinal sliding movement relative to the casing 5. Finger 38 is pivoted at its rear end to the bottom of casing 5 as at 41, for lateral swinging movement. Finger 37 has a laterally and forwardly extending lug portion 42 at its inner side which engages in a correspondingly extending slot or recess 43 in the adjacent side of finger 38. A spring 44 acts to yieldingly urge the finger 38 toward finger 37, and when this is permitted finger 37 is simultaneously caused to have a forward sliding movement due to the engagement of the obliquely extending lug 42 in the similarly extending slot 43 of finger 38. Fixed to and projecting upwardly from the finger 38 forwardly of its pivot 41 is a pin 45 that engages in a slot 46 provided in the front end of a plate 23. One side of slot 46 is obliquely disposed with respect to the longitudinal axis of the casing 5, the arrangement being such that when plate 23 is shifted forwardly, it acts upon pin 45 to swing finger 38 away from finger 37. When this happens, the engagement of lug 42 in slot 43 brings about a rearward sliding movement of finger 37 so that the needle eye is released when the threading pin 17 is retracted. On the other hand, when plate 23 is slid rearwardly it disengages from pin 45, thereby allowing spring 44 to swing finger 38 toward finger 37. The latter action brings about forward movement of finger 37 and swinging movement of finger 38 toward finger 37 so that said fingers will act to rotate the needle and then tightly grip the needle eye therebetween, holding the needle in position so that its eye is properly registered with the threading pin 17 and insuring proper passage of plate 23 continues to bring about the threading stroke of threading pin 17. As previously noted, forward movement of plate 23 causes retraction of the threading pin 17 and thence causes finger 38 to swing away from finger 37 against the action of spring 44, simultaneously shifting finger 37 rearwardly to release the needle. It will be noted that at the inner side of slot 46, plate 23 has a nose portion 47 that moves into close proximity to the jaw portion 48 of rib 7 when plate 23 reaches its forward limit of movement and immediately after the fingers 37 and 38 are released from the needle and threading pin 17 has been retracted from the needle eye. In this way, the

nose portion 47 coacts with the jaw portion to tightly clamp the thread loop and prevent its withdrawal from the needle eye. Thus, when the needle is elevated the thread loop 18 is pulled further through the needle eye until one end of the thread passes completely through said needle eye, thereby completing the threading operation. By then holding the thread and needle against relative displacement, disengagement of the thread from between the nose portion 47 and jaw portion 10 may be manually effected with slight effort upon slight rearward movement of plate 23.

A longitudinally split needle guide 48 is carried by a bracket 49 fixed upon the top of casing 5 so that the passage of guide 48 is vertically aligned with the needle seat 14. Thus, when a needle is inserted downwardly through the guide 48 with its eye portion lowermost, said eye portion will be effectively guided to the seat 14 and the needle will be supported in proper vertical position for being threaded. As the guide 48 is split longitudinally as indicated at 50, the thread may be disengaged from said guide 48 when the needle is withdrawn therefrom after completion of the threading operation.

It is important to maintain the loop thread in a taut condition preparatory to and during the threading operation and while a portion of the thread is disposed in the slot 12 for being forced in the form of a loop through the needle eye. For this purpose, a thread tension device of any well known or preferred construction is rigidly mounted as indicated at 51 upon one side of the forward end portion of the casing 5, said tension device being such that it may have the two strands of the looped end of the thread readily engaged in the same or disengaged therefrom. When the thread has been properly looped and engaged in the tension device 51, the pin 29 is forced rearwardly to bring about the threading operation in the manner already described. After completion of the threading operation, the thread is disengaged from the tension device 51 and the threaded needle is withdrawn from the device.

From the foregoing description, it is believed that the construction and operation, as well as the advantages of the present invention, will be readily understood and appreciated by those skilled in the art.

In actual practice, the present device has been found very efficient for the intended purpose and the organization of parts is such as to insure long continued efficient operation without requiring adjustment or repair. While I have illustrated and described a preferred construction in considerable detail, it will be apparent that minor changes may be made such as fall within the spirit and scope of the invention as claimed.

What I claim as new is:

1. A device for threading hand sewing needles comprising a casing, a threading pin mounted to slide transversely in the casing, guide means in the path of the pin and of the needle for receiving a loop of thread, a lever connected to the pin for moving the pin to carry the loop through the eye of the needle, a horizontal actuating plate mounted in the casing for horizontal rectilinear movement, a single spring connected to the lever and to the actuating plate adapted to be compressed when the actuating plate is moved rearwardly and adapted to expand and withdraw the threading pin from the eye of the needle when the actuating plate is moved forwardly, and coop-

erating members on the actuating plate and the casing for clamping the loop of thread stationary when the clamping plate reaches its forward limit of movement immediately after the pin is withdrawn from the needle after threading the latter.

2. A threading device for hand sewing needles, comprising a casing, a threading pin mounted to slide transversely in the casing, a guide means in the path of the pin and of the needle for receiving a loop of thread, a lever connected to the pin for moving the pin to carry the loop through the eye of the needle, an actuating plate mounted in the casing for rectilinear movement, a single spring connected to the lever and to the actuating plate adapted to be compressed when the actuating plate is moved rearwardly and adapted to extend and withdraw the threading pin from the eye of the needle when the actuating plate is moved forwardly, a seat in the casing to rotatably support the eye end of the needle with the latter in alignment with the threading pin, spring actuated fingers for automatically rotating the needle and then clamping the eye end of the latter to bring and retain said eye in registry with the threading pin when the actuating plate is moved rearwardly, and means to automatically release the fingers from the needle upon movement of the actuating plate forwardly, said last-named means including coacting members respectively carried by one of said fingers and said actuating plate.

3. A threading device for hand sewing needles, comprising a casing, a threading pin mounted to slide transversely in the casing, a guide means in the path of the pin and of the needle for receiving a loop of thread, a lever connected to the pin for moving the pin to carry the loop through the eye of the needle, an actuating plate mounted in the casing for rectilinear movement, a single spring connected to the lever and to the actuating plate adapted to be compressed when the actuating plate is moved rearwardly and adapted to extend and withdraw the threading pin from the eye of the needle when the actuating plate is moved forwardly, a seat in the casing to rotatably support the eye end of the needle with the latter in alignment with the threading pin, spring actuated fingers for automatically rotating the needle and then clamping the eye end of the latter to bring and retain said eye in registry with the threading pin when the actuating plate is moved rearwardly, and means to automatically release the fingers from the needle upon movement of the actuating plate forwardly, said last-named means including a pin fixed to and rising from one of the fingers, said actuating plate having a cam slot receiving said pin and having an oblique side wall acting on the pin to retract the associated finger when said actuating plate moves forwardly.

4. A threading device for hand sewing needles, comprising a casing, a threading pin mounted to slide transversely in the casing, a guide means in the path of the pin and of the needle for receiving a loop of thread, a lever connected to the pin for moving the pin to carry the loop through the eye of the needle, an actuating plate mounted in the casing for rectilinear movement, a single spring connected to the lever and to the actuating plate adapted to be compressed when the actuating plate is moved rearwardly and adapted to extend and withdraw the threading pin from the eye of the needle when the actuating plate

is moved forwardly, a seat in the casing to rotatably support the eye end of the needle with the latter in alignment with the threading pin, spring actuated fingers for automatically rotating the needle and then clamping the eye end of the latter to bring and retain said eye in registry with the threading pin when the actuating plate is moved rearwardly, and means to automatically release the fingers from the needle upon movement of the actuating plate forwardly, one of said fingers having an oblique slot, the other finger being slidably mounted for movement longitudinally of the casing and having an oblique lug projecting therefrom into said oblique slot whereby retraction of the first-named finger will automatically cause retraction of the other finger and swinging movement of the first-named finger toward the second-named finger will automatically cause forward movement of said second-named finger.

5. In a threading device for hand sewing needles, needle rotating and clamping means for registering the eye of the needle with a threading pin and securing the needle eye in such registered position, comprising a clamping finger mounted for sliding movement toward and from the needle, a second finger pivotally mounted for movement toward and away from the first-named finger, said first-named finger having a forwardly extending oblique lug on one side thereof, the other finger having a similarly extending oblique slot slidably receiving said lug, a spring normally acting to swing the second-named finger toward the first-named finger, and means to operatively connect the second-named finger with an actuating plate.

6. In a needle threading device, a casing, a threading pin mounted to slide transversely in the casing, a guide means in the path of the pin and of the needle for receiving a loop of thread, a lever connected to the pin for moving the pin

to carry the loop through the eye of the needle, an actuating plate mounted in the casing for pivotal and rectilinear movement, means for manually moving said actuating plate, a single spring connected to the lever and to the actuating plate adapted to be compressed when the actuating plate is moved rearwardly and adapted to expand and withdraw the threading pin from the eye of the needle when the actuating plate is moved forwardly, said actuating plate having a longitudinal elongated slot provided at its forward end with a lateral extension, a guide pin carried by the casing and projecting into said slot, said spring being connected to the actuating plate to pivotally swing the latter and allow passage of the guide pin into said slot extension in case the actuating plate is fully moved rearwardly, said lever and said actuating plate having contracting members for swinging the actuating plate so as to disengage the guide pin from the slot extension when threading movement of the threading pin is completed.

7. A device for threading hand sewing needles, comprising a casing, a floating threading pin mounted to slide transversely in the casing, guide means in the path of the pin and of the needle for receiving a loop of thread, a lever connected to the pin for moving the pin to carry the loop through the eye of the needle, an actuating member in the casing, and a single spring connected to the lever and to the actuating member and adapted to be compressed when the actuating member is moved in one direction and to expand and withdraw the threading pin from the eye of the needle when the actuating plate is moved in the opposite direction, said lever having a slot at one end, said threading pin having an angularly bent end loosely disposed in said slot.

JOHN C. LOUNSBURY.
